UNITED STATES PATENT OFFICE.

HOWARD McGAW SMYTH, OF BERKELEY, CALIFORNIA.

PORTABLE DESK BOOK REST.

Application filed January 3, 1924. Serial No. 684,139.

The object of my invention is to provide a portable holder for books, copy, and the like which may be conveniently set on any table top, and which is adapted for being arranged to hold the book in position to be readily read.

The particular object of my invention, furthermore, is to provide an inexpensive, durable book rest, preferably made of wood, and at the same time of such construction that the parts are capable of supporting safely books of some weight.

To this end, my invention comprises a base or foot adapted for being set on a table top; a post pivotally mounted on said foot and adjustable in a vertical plane, the pivotal means including devices for securing the post in place as adjusted; companion arms having the inner ends pivoted to the upper end of said post and adjustable in a plane making an angle with the plane of the pivot axis of the post; and racks carried by said arms.

Other details of construction and the operation of my book rest or support are herein-after fully described, with reference to the accompanying drawings, in which:

Fig. 1 is a perspective view of my improved book rest showing its preferable construction;

Fig. 2 is a side elevation of my book rest, as shown in Fig. 1;

Fig. 3 is a top view of my book rest with the parts somewhat differently arranged relatively to each other than as shown in the preceding views;

Fig. 4 shows details of construction in perspective of the arms of my book rest;

Fig. 5 shows a perspective of my book rest with the base or foot thereof, and the post pivoted on the latter somewhat modified in construction with respect to that shown in the preceding views;

Fig. 6 is a longitudinal sectional view of the modified book rest, shown in Fig. 5, also illustrating in dotted lines, the adjustments which may be made of the post; and

Fig. 7 is a plan or top view of my modified book rest as appearing in one adjustment thereof.

My book rest, as shown in Figs. 1 to 3 inclusive, comprises a base or foot 1 adapted to be stood on a table top. The foot is provided with two spaced perpendicular ears. Between said ears is pivoted the lower end of the post 3 by a screw bolt 4 on which is

threaded a thumb nut 5. The upper end 3^a of said post 3 is slotted, as at 6, to receive the inner ends of the arms 7, 7 and on the latter are mounted the book-supporting racks 8. 60

By curving the post 3, as shown in Figs. 1 and 2 of the drawings, and making the plane of the slot 6, provided in the upper end of said post to extend at an angle with the plane of the axis on which the post is 65 pivotally mounted on the foot, I provide a book rest which may be readily adjusted to support the book at any angle convenient to the reader; furthermore, the devices so combined provide a very efficient, simple 70 and inexpensive book rest.

The racks 8 comprise a back 8^a and a flange 8^b along the lower edges, the latter being adapted to support the book in place.

The inner ends of the arms 7 are recessed 75 so as to be adapted to be placed one on the other. Thus the so overlapped inner ends of said arms have the same thickness as the other portions of these arms. The arms are pivoted in place by a screw-bolt 11 inserted 80 through holes 10 therefor provided on the inner ends of said arms; and on said screw bolt is threaded a thumb-nut 12, preferably seated on a washer 13.

The book rest shown by Figs. 5, 6 and 7 85 is, in substance, like the book rest just described with the following exceptions: The post is jointed so as to permit it being made of two straight pieces instead of a single curved piece like the post 3. The base or 90 foot of my book rack is also somewhat modified in construction. Referring to the details shown in Figs. 5 to 7 inclusive: The base 14 is made substantially T-shaped. The base is grooved, as at 15, to provide a 95 slot in which the lower end of the lower member of the post 16 is pivotally mounted by a screw-bolt 17 provided with a clamping thumb nut 17^a. I further provide a recess 14^a in the base or foot 14 in which to insert 100 a counter-weight 14^b. The upper end of the lower piece 16 of the post is slotted as at 18, and in such slot is pivotally mounted one end of the upper piece 19 of the post by means of a screw-bolt 22, on which is threaded 105 a clamping thumb-nut 23. The upper piece 19 of this post is slotted as at 20, and therein are mounted the inner ends of the arms 21, 21, which are of similar construction as the arms 7, 7, previously described. Said 110 arms 21, 21 are adjustably secured in place by a screw-bolt 27 on which is threaded a

2
clamping thumb-nut 24. On the arms 21, 21 are fixed racks 25, 25 of similar construction as the racks 8^a.

I claim:

5 A portable desk book rest, comprising a flat base, a pair of vertical ears extending upwardly from the base and provided with aligned perforations, a post fitted between the perforated vertical ears and extending 10 upwardly therefrom, the upper portion of the post being extended forwardly and provided at its free end with a horizontally disposed slot, a screw extending through the perforations in the vertical ears and the

lower end of the post, a thumb nut engaging the threaded end of the screw, a pair of arms having their inner ends perforated and reduced in thickness and overlapping the reduced overlapping ends of the arms fitting in the horizontally disposed slot in the free end of the post, a screw extending through the upper slotted end of the post and the perforations in the overlapping reduced ends of the arms, a thumb nut engaging the threaded end of the last mentioned screw, and a book rest carried by the free outer end of each arm.

HOWARD McGAW SMYTH.
